UNITED STATES PATENT OFFICE.

SALVATORE SANNA, OF OLINGHOUSE, NEVADA.

DUPLEX ROTARY STEAM-TURBINE.

1,032,300.

Specification of Letters Patent.

Patented July 9, 1912.

Application filed September 19, 1911. Serial No. 650,155.

To all whom it may concern:

Be it known that I, SALVATORE SANNA, a citizen of the United States, residing at Olinghouse, in the county of Washoe and State of Nevada, have invented new and useful Improvements in Duplex Rotary Steam-Turbines, of which the following is a specification.

The invention relates to turbines, and 10 more particularly to the class of duplex rotary steam turbines.

The primary object of the invention is the provision of a turbine in which the full steam pressure will be utilized prior to its 15 exhaust from the same for obtaining a uniform and maximum speed in the operation of the turbine.

Another object of the invention is the provision of a turbine in which there are arranged spaced stationary and rotary vane wheels, the rotary vane wheels being mounted upon a common shaft for driving the same, and steam will be admitted to the rotary vane wheels in successive order, thereby 25 forming a high and low pressure side to the turbine, thus enabling the utilization of the steam pressure to its full extent prior to the exhaustion thereof from the turbine for obtaining maximum speed.

30 A further object of the invention is the provision of a turbine of this character which is simple in construction, possessing few parts, reliable and efficient in operation, and inexpensive in manufacture, and also 35 one that will be least liable to get out of order.

With these and other objects in view, the invention consists in the construction, combination and arrangement of parts, as will be hereinafter more fully described, illustrated in the accompanying drawings, and pointed out in the claims hereunto appended.

40 In the drawings: Figure 1 is a side elevation of a turbine constructed in accordance with the invention. Fig. 2 is a vertical longitudinal sectional view thercof. Fig. 3 is an enlarged fragmentary vertical sectional view through the steam chest. Fig. 4 is a plan view of one of the rotary vane wheels.

Similar reference characters indicate corresponding parts throughout the several views of the drawings.

50 Referring to the drawings by numerals, the turbine comprises a base 5, upon which are mounted vertical supporting bearings 6,

in which is journaled a rotatable shaft 7, the bearings 6 being formed with oil pockets 8 communicating with oil ducts 9, so that lubricant may be supplied to the shaft 7, 60 while being rotated. Surrounding the shaft 7 are spaced stationary vane disks 10 and 11, respectively, the same being supported upon base standards 12 mounted upon the base 5, and rising vertically therefrom, the 65 said stationary vane disks 10 and 11 being formed on their faces with spaced annular rows of diagonally disposed steam vents 13, which coöperate with reversely disposed diagonal steam vents 14 arranged in spaced 70 annular rows upon adjacent faces of rotary disks 15 and 16, respectively, the vents 13 and 14 on both the stationary and rotary disks 10 and 11—15 and 16 being concentrically arranged with respect to the shaft 7. 75 The said rotary disks are fixed to the said shafts 7 to impart rotary movement thereto, in a manner presently described.

Formed on the stationary disks 10 and 11 are outwardly extending hubs 17 and 18, the 80 latter of which surrounds the shaft 7, while the hub 17 surrounds a governor operating shaft 19, the latter journaled, near its outer end, in a bearing 20 fixed to a governor stand 21 supported upon the base 5, at one 85 end of the turbine, the governor operating shaft 19 being integral with one end of the shaft 7 to rotate therewith. The hubs 17 and 18 form steam inlet chambers 22, and are provided with inlet ports 23, at their inner ends, communicating with the innermost row of vents 13 formed on the inner faces of the stationary disks 10 and 11, so that on the admission of steam between the said stationary and rotary disks the latter will be 95 caused to rotate for transmitting similar movement to the shaft 7 which has fixed thereto, between the said disks, a belt pulley 24, over which is adapted to be trained a belt or the like (not shown) for driving 100 machinery.

Fixed at the peripheries of the stationary disks 10 and 11 and on the inner faces thereof are cylinder heads 25 which are designed to inclose the rotary disks 15 and 16 and 105 form casings therefor, so as to prevent the possibility of the escape of steam admitted between the stationary and rotary vane disks, in the operation of the turbine, the said shaft 7 being passed centrally through the cylinder heads 25 which are provided with stuffing boxes 26 surrounding the said 110

shaft to prevent the leakage of steam therebetween in the operation of the turbine.

Formed on the stationary disk 10 and the adjacent cylinder head 25, at the peripheries thereof, is a nipple 27, to which is connected one end of a steam pipe 28, the opposite end of which is formed with an elbow 29 connected with the hub 18, and communicating with the chamber 22 formed thereby, so that 10 steam will pass from between the stationary and rotary disks 10 and 15 to the stationary and rotary disks 11 and 16, thereby effecting high and low pressure sides to the turbine. Connected with the stationary disk 11 and the adjacent cylinder head 25, at the peripheries thereof, is a nipple 30, to which is connected a steam exhaust pipe 31, the latter leading to the atmosphere, so that the expanded or utilized steam from the low pressure side of the turbine may be exhausted 20 through the said exhaust pipe 31 to the atmosphere, as will be clearly obvious.

Mounted upon the hub 17, at the top thereof, is a steam chest 32 with which communicates a steam supply pipe 33 which is provided with the usual cut-off valve 34 and the throttle valve 35, the latter being provided with a regulating arm 36, connected with an adjustable stem 37 which is also 30 connected with one end of a weighted lever 38 fulcrumed, as at 39, in a supporting bracket 40 rising from the governor stand 21, the weighted lever 38 being pivotally connected to a lifting link 41 which is 35 also pivoted to an inertia governor mechanism 42 mounted upon a rotary counter shaft 43 journaled in a bearing 44 rising from the said governor stand 21, the counter shaft 43 being provided with a worm gear 40 fixed thereto and meshing with a companion worm gear 46 fixed to the governor operating shaft 19, so that upon excessive rotation of the shaft 7, the governor mechanism 42 will be operated, so as to raise the 45 link 41 and through the medium of the weighted lever 38, adjustable stem 37, and the throttle arm 36, the said throttle valve 35 will be adjusted to regulate or decrease the steam supply through the inlet steam 50 pipe 31 to the steam chest 32, as the occasion may require.

Formed in the top of the hub 17 on the stationary disk 10 are steam inlet ports 47, the same being provided with valve seats 48, in which are adapted to be alternately seated balancing check valves 49, the latter being operated upon by means of cams 50 fixed to the throttle operating shaft 19, these 60 cams being timed or set, so as to alternately open the said balance check valves 49 for admission of steam from the steam chest 32 to the chamber 22, whence such steam will be delivered to the vanes on the stationary and rotary disks 10 and 11 at the high pressure side of the turbine, and as the steam

progresses from the center of the said disks to the peripheries thereof, it will be conveyed therefrom through the pipe 28 between the stationary and rotary vane disks 11 and 16, at the centers thereof, whence 70 the said steam will expand and pass to the peripheries of the said last-named disks, and finally discharge through the exhaust pipe 31 to the atmosphere.

Formed on the balance check valves 49 are 75 stems 51 carrying balancing pistons 52, working within cylinders 53 mounted upon the steam chest 32, each cylinder being formed with a by-pass 54, whereby steam from the steam chest 32 on the opening of the valve 51 80 therein may pass from one side of the piston 52 through the by-pass 54 to the opposite side thereof within the cylinder 53, so as to exert a downward pressure upon the piston 52 to move the valve 51 in closing position, when the cam 50 has completed a half revolution after acting upon the valve for the opening thereof, thus causing a positive closing of the said valve 51. When the valve 51 is closed, the piston 52 will move 90 sufficiently to uncover an exhaust port 55 formed in one side of the cylinder, which port communicates with an exhaust union 56, so that the steam between the said piston 52 and the outer end of the cylinder 53 may 95 be exhausted through said union. When the piston 52 uncovers the port 55, it simultaneously closes the inner end of the by-pass 54, thereby closing the same to prevent the possibility of steam passing from the steam 100 chest 32 between the piston 52 and the outer end of the cylinder. It will be noted that these check balancing valves will be easy of operation, and the same will exert only their own weight upon the cams 50 when being 105 operated thereby.

Carried at the outer ends of the hubs 17 and 18 of the stationary vane disks 10 and 11 are packing glands 57 which are of the ordinary well-known construction and surround both the shaft 7 and the governor operating shaft 19, so as to prevent leakage from the chambers 22 formed by the said hubs between the same and the said shafts. Also arranged within the chambers 22 at 110 the inner end of the hubs 17 and 18 are suitable packing glands 58 which surround the said shafts 7 and 19, respectively, and work against the rotary disks 15 and 16, so as to prevent any leakage of steam from the said 120 chambers 22 between the said rotary disks 15 and 16, and said shafts during the operation of the turbine.

Keyed to or otherwise secured to the free end of the shaft 7 is a clutch or coupling 125 head 59, whereby an additional turbine may be connected therewith, which turbine is adapted to be of a construction, hereinbefore described, although the stationary and rotary vane disks thereof may have the steam 130

vanes thereon reversely arranged with respect to the vanes 13 and 14, upon the stationary and rotary disks 10 and 11—15 and 16. Thus in this manner, the shaft may be 5 reversely rotated if desired. Of course, it is understood that both of the turbines will not be operated simultaneously, but the connection of the last turbine with the shaft 7 is only active when it is desired to rotate the 10 shaft in a reverse direction, when the other turbine is inactive.

At opposite sides of the outermost supporting bearing 6 and keyed to the shaft are formed end thrust collars 60, between which 15 and the adjacent faces of said vertical supporting bearings 6 are arranged bearing balls 61, which are confined within annular race-ways 62 receiving the same, and these collars 60 prevent end thrust of the shaft 7, 20 when being rotated by the turbine.

What is claimed is:

1. A turbine of the class described, comprising spaced stationary vane disks, rotary vane disks coöoperative with said stationary 25 vane disks, a common shaft connecting the said rotary vane disks, hubs formed on said stationary vane disks and forming inlet chambers communicating with the said stationary and rotary vane disks, a conveyer 30 pipe communicating with the hub of one stationary disk and leading to the periphery

of the other stationary disk, an exhaust pipe leading from the periphery of the other stationary disk, a steam chest having communication with one of the hubs and having a 35 supply pipe leading thereto, means for shutting off the supply through the supply pipe to the said steam chest, packing glands closing the outer ends of said hubs and surrounding said shaft, and packing glands arranged within the hubs and closing the inner ends thereof. 40

2. A turbine of the class described, comprising spaced stationary and rotary vane disks, a common shaft connecting said rotary disks, hubs formed on said stationary disks, a communication between said stationary disks, exhaust means connected to one of said stationary disks, steam supply means communicating with one of said hubs, 50 means for shutting off said steam supply, packing glands closing the outer ends of said hubs and surrounding said shaft, the packing glands arranged within said hubs, 55 and closing the inner ends thereof.

In testimony whereof I affix my signature in presence of two witnesses.

SALVATORE SANNA.
